UNITED STATES PATENT OFFICE

150,726

DESIGN FOR A RING

Thomas Vincent Phelan, Trenton, N. J.

Application July 18, 1947, Serial No. 140,363

Term of patent 14 years

(Cl. D45—10)

To all whom it may concern:

Be it known that I, Thomas Vincent Phelan, a citizen of the United States, residing at Trenton, in the county of Mercer and State of New Jersey, have invented a new, original, and ornamental Design for a Ring, of which the following is a specification, reference being had to the accompanying drawing, forming part thereof.

Fig. 1 is a top plan view of a ring, showing my new design.

Fig. 2 is an elevational view thereof, and
Fig. 3 is an edge view of the same.

I claim:

The ornamental design for a ring, as shown.
THOMAS VINCENT PHELAN.
